UNITED STATES PATENT OFFICE

2,564,727

MECHANICAL PENCIL

Herbert W. Sams, Atlanta, Ga., assignor to
Scripto, Inc., a corporation of Georgia

Application April 7, 1948, Serial No. 19,469

7 Claims. (Cl. 120—18)

1

This invention relates to mechanical pencils having a screw type lead feed mechanism, and more especially to an improved construction for pencils of this sort in which a novel form of ejector pin is incorporated which eliminates end play in the lead feed, and in which the lead feed mechanism is otherwise arranged for assembly in the pencil so that particularly smooth operating characteristics are obtained.

Also, according to the present invention, the various elements of the pencil construction are arranged to insure alignment of the barrel and the lead feed mechanism upon assembly.

The present invention is described in detail below in connection with the accompanying drawing, in which:

Fig. 1 is a vertical section of a mechanical pencil constructed in accordance with the present invention;

Fig. 2 is a section taken on the line 2—2 in Fig. 1;

Fig. 3 is a section taken on the line 3—3 in Fig. 1;

Fig. 4 is an enlarged detail of the writing point of the pencil as seen from the right side in Fig. 1 with the lead feed mechanism in full downward position;

Fig. 5 is a detail of the ejector pin and lead grip sleeve;

Fig. 6 is a corresponding, partly fragmentary, right side detail;

Fig. 7 is a sectional detail taken on the line 7—7 in Fig. 5; and

Fig. 8 is a fragmentary detail illustrating the manner in which the lead feed mechanism is assembled.

As shown in the drawing, the mechanical pencil of the present invention comprises a barrel 10 preferably formed of moulded plastic and having separate upper and lower portions 11 and 12. The upper portion 11 of the barrel 10 serves as an operating cap, and may be fitted in any convenient manner with a pocket clip 13 if desired, while the lower portion 12 provides an anchoring housing for a lead feed mechanism 14.

The lead feed mechanism 14 is arranged as a unit assembly for disposition in the barrel 10 and includes a helically slotted feed tube 15, a longitudinally slotted guide tube 16, and a lead carrying and ejecting mechanism consisting of a lead grip sleeve 17 and an ejector pin 18.

As mentioned above, the lead feed mechanism 14 is assembled as a unit, and for this purpose the guide tube 16 is fitted with a mounting sleeve 19 at its lower end, this mounting sleeve 19 being

2

keyed with and retained on the guide tube 16 by a dimple or boss formed in the guide tube to fit a slot in the end of the mounting sleeve as illustrated at 20 in Fig. 1. Also, the feed tube 15, which is disposed in telescoped relation for rotation on the guide tube 16, is fitted with a lock sleeve 21 similarly keyed and retained in position by a projection or boss on the guide tube engaging a slot in the lock sleeve as indicated at 22 in Fig. 1. The feed tube 15 and guide tube 16 are telescoped so that the lower end face of the lock sleeve 21 rests on the top end face of the mounting sleeve 19, a fiber washer 23 being interposed to provide for smooth relative rotation of these sleeves.

The lead feed mechanism 14 is anchored in the lower portion 12 of the barrel 10 by a press fit of the mounting sleeve 19 in the writing end of the lower portion 12 which is constricted as 20 shown in the drawing. When pressed in place, a portion of the mounting sleeve 19 extends from the writing end of the lower barrel 12, and this extending portion of the mounting sleeve 19 is formed with external threads 24 to receive an 25 internally threaded, metal, tip member 25. The writing end of this lower barrel portion 12 is shouldered as shown at 26 and the tip member 25 is formed with a flange 27 adapted to seat externally on this shoulder 26 and thereby align the lower barrel portion 12 with the tip member 25.

Alignment of the parts is particularly important at this point, because any surface irregularity between associated parts at the writing end of the pencil not only impairs its appearance but is an annoyance in use when the pencil is grasped at this portion for writing. The above described arrangement of the flange 27 on the tip member 25 for seating externally on the shoulder 26 at the writing end of the lower barrel portion 12 is especially well adapted for obtaining effective alignment of the parts when a moulded plastic barrel is used in the pencil construction. Molded plastic parts have a tendency to give or spread under pressure in assembly, and the arrangement of the flange 27 on the tip member 25 not only forces alignment of the lower barrel portion 12 but contains it against the mounting sleeve 19 so that it cannot give or spread.

Operation of the lead feed mechanism 14 is provided for through an operating sleeve 28 which is fitted snugly, but freely for rotation, in the lower barrel portion 12, and is contracted at its lower end, as indicated at 29 in Fig. 1, to grip 55 the lock sleeve 21 fitted on the feed tube 15.

The operating sleeve 28 extends beyond the upper end of the lower barrel portion 12 so that the upper barrel portion 11 may be fitted over it as well, and flats 30 are formed in a portion of this extending length to set up ribs 31 for frictional contact with the upper barrel portion 11 (compare Figs. 1 and 3). As the guide tube 16 is fixed in the lower barrel portion 12 by the mounting sleeve 19, this frictional contact of the upper barrel portion 11 with the operating sleeve 28 allows the lead feed mechanism 14 to be actuated from the upper barrel portion 11 through the lock sleeve 21 keyed on the feed tube 15 and to which the operating sleeve 28 is fixed.

The operating sleeve 28 is further formed with a circumferential expanded portion 32 positioned in correspondence with the joint between the upper and lower barrel portions 11 and 12 for aligning the barrel portions at this point. Also, the upper barrel portion 11 is advantageously fitted at this joint with an external ring member 33 to condition it, similarly to the writing end of the lower barrel portion 12, against giving or spreading as a result of repeated removal and replacement of the upper barrel portion 11 on the operating sleeve 28 during use of the pencil.

Internally the operating sleeve 28 is fitted with spacing members 34 which are disposed as shown in Figs. 1, 2, and 3 to support the feed tube 15 in alignment with the operating sleeve 28. These spacing members 34 also serve as partitions forming compartments adapted to receive reserve leads 35, and an eraser 36 may be disposed in the upper end of the operating sleeve 28 as a closure for the reserve lead compartments.

The lead carrying and ejecting mechanism incorporated in the lead feed mechanism 14 according to the present invention is of the same general type illustrated and described in U. S. Patent No. 2,362,727, issued November 14, 1944, to B. D. Smith. A lead grip sleeve 17 is provided in the present case, as in the above noted prior patent, to grip and position a lead 37 for feeding by the lead feed mechanism 14. The grip sleeve 17 is formed with a recess or pocket defined by a lateral flange 38 (compare Fig. 5) proportioned to receive a lug 39 on the associated ejector pin 18, and to ride with the lug 39 in the longitudinal slot in the guide tube 16 so that the grip sleeve 17 and ejector pin 18 are retained in proper spaced relation during normal feeding movement. The longitudinal slot in the guide tube 16 is relieved near its lower end as shown at 40 in Fig. 4 to provide clearance for turning movement of the lateral flange 38 so that the grip sleeve 17 may rotate upon substantial exhaustion of the lead 37 to bring the lug 39 into alignment with a slot 41 in grip sleeve 17 and thus allow downward movement of the ejector pin 18 in the grip sleeve 17 to eject the exhausted lead as illustrated in Fig. 4. Reference is made to the above noted prior Patent No. 2,362,727 for further details of the arrangement and operation of the lead carrying and ejecting mechanism in this manner.

Feeding movement of the lead carrying and ejecting mechanism results from engagement of the helical slot in the feed tube 15 by the ejector pin 18, and the lead carrying and ejecting mechanism employed according to present invention differs over the one disclosed in the above prior Patent No. 2,362,727 principally in the improved arrangement by which the ejector pin 18 is adapted for engaging the feed tube 15. Ejector pins used in the lead feed mechanisms of mechanical pencils are commonly formed with a lug dis-

posed to extend through a longitudinal slot in a guide tube and engage a helical slot in a feed tube so that relative rotation of the feed tube and guide tube causes feeding movement of the ejector pin. This same general arrangement is used according to the present invention, but with an improved arrangement of spaced lugs 42 on the ejector pin 18 for engaging the feed tube 15 so that end play in the lead feed is eliminated and a particularly smooth feeding movement is obtained.

The spaced lugs 42, as illustrated in detail in Figs. 5, 6 and 7 of the drawing, are disposed on the extending edge of a lateral projection 43 formed on the ejector pin 18 to extend through the longitudinal slot in the guide tube 16. These lugs 42 are formed with wing portions as shown extending transversely over the exterior surface of the guide tube 16 and oriented at an angle for engaging the helical slot in the feed tube 15, and the lugs 42 are spaced to ride opposed faces of successive turns of the helical slot. That is, the spacing of the lugs 42 is proportioned to ride the opposed faces (i. e., the opposite edge faces) presented by the body of the feed tube 15 between successive turns of the helical slot. As a result, the lugs 42 may be formed to ride more or less loosely in the helical slot for smooth and easy feeding movement and yet be associated with the feed tube 15 so that all objectionable end play is avoided.

A further feature of this arrangement of the ejector pin 18 is that between the spaced lugs 42 the lateral projection 43 is formed to extend slightly from the longitudinal slot in the guide tube 16 to ride the interior face of the feed tube 15 so that the lugs 42 are prevented from projecting beyond the exterior face of the feed tube 15 which would jam the lead feed mechanism. Also, as the lugs 42 are formed with wing portions extending transversely over the exterior surface of the guide tube 16, the disposition of the lateral projection 43 to ride the interior surface of the feed tube 15 contains the ejector pin 18 against lateral shifting and thus additionally stabilizes the operation of the lead feed mechanism.

Smooth operating characteristics are also obtained by virtue of means employed according to the present invention for assembling the lead feed mechanism as a unit. This means, which is illustrated best in Fig. 8 of the drawing, comprises a relatively thin, flexible, metallic washer 44 fitted over the upper extending end of the guide tube 16 and resting on the end face of the feed tube 15, a fiber washer 45 superimposed on the flexible washer 44, and a second, relatively rigid, metallic washer 46 superimposed on the fiber washer 45. Upon assembly of the lead feed mechanism, ears 47 are struck out in the guide tube 16 adjacent the longitudinal slot and a dimple or boss 48 is formed diametrically opposite the longitudinal slot for retaining the superimposed washers 44, 45, and 46 pressed against the end face of the feed tube 15. Under this pressure the flexible washer 44 is flexed into the opening of the helical slot in the end face of the feed tube 15 which causes the flexible washer 44 to rotate with the feed tube 15 and thus insures metal on fiber friction between the flexible washer 44 and the fiber washer 45 during operation of the lead feed mechanism.

The present invention has been illustrated and described above in connection with a preferred embodiment in which the features of the invention are particularly well suited for use. However, it will be recognized that these features are

also adapted for general use otherwise in mechanical pencil constructions, and such general application of the invention is contemplated by the appended claims.

1. claim:

1. In a mechanical pencil having a lead feed mechanism including a helically slotted feed tube of uniform pitch throughout its length and a longitudinally slotted guide tube disposed for relative rotation inside said feed tube, a lead carrier adapted for longitudinal displacement in said guide tube and an associated ejector pin formed with spaced lugs, said lugs being formed to extend through the longitudinal slot in said guide tube for desposition in the helical slot in said feed tube and being spaced to ride the opposite edge faces presented by the body of said feed tube between successive turns of said helical slot, and said ejector pin having a lateral projection extending between said lugs and disposed in the longitudinal slot in said guide tube to ride the interior face of said feed tube and thereby prevent said lugs from projecting beyond the exterior face of said feed tube.

2. In a mechanical pencil having a lead feed mechanism including a helically slotted feed tube of uniform pitch throughout its length and a longitudinally slotted guide tube disposed for relative rotation inside said feed tube, a lead carrier adapted for longitudinal displacement in said guide tube and an associated ejector pin formed with a lateral projection disposed in the longitudinal slot in said guide tube and having spaced lugs formed on said projection, said lugs being formed for desposition in the helical slot in said feed tube and being spaced to ride the opposite edge faces presented by the body of said feed tube between successive turns of said helical slot, and said lateral projection being formed to ride the interior face of said feed tube and thereby prevent said lugs from projecting beyond the exterior face of said feed tube.

3. In a mechanical pencil having a lead feed mechanism including a helically slotted feed tube of uniform pitch throughout its length and a longitudinally slotted guide tube disposed for relative rotation inside said feed tube, a lead carrier adapted for longitudinal displacement in said guide tube and an associated ejector pin formed with a lateral projection disposed in the longitudinal slot in said guide tube and extending slightly from said slot to ride the interior face of said feed tube, and spaced lugs formed on the extending edge of said lateral projection, said lugs being formed with wing portions extending transversely over the exterior surface of said guide tube and oriented at an angle for desposition in the helical slot in said feed tube, and said lugs being spaced to ride the opposite edge faces presented by the body of said feed tube between successive turns of said helical slot.

4. A mechanical pencil comprising a barrel having a lower portion and an upper portion, a lead feed mechanism including a helically slotted feed tube and a longitudinally slotted guide tube, said guide tube being fixed at one end in the lower portion of said barrel, and said feed tube being assembled in telescoped relation for rotation on said guide tube, means adapting said feed tube for rotation by the upper portion of said barrel, and means disposed at the extending end of said guide tube for retaining said feed tube in assembled relation comprising a relatively thin, flexible, metallic washer fitted over said guide tube and resting on the end face of

said feed tube, a fiber washer superimposed on said flexible washer, and a relatively rigid metallic washer superimposed on said fiber washer, said guide tube having positioning means at its extending end for retaining said washers pressed against the end face of said feed tube, whereby said flexible washer is flexed into the opening of the helical slot in the end face of said feed tube thereby causing said flexible washer to rotate with said feed tube and insuring metal on fiber friction between said flexible washer and said fiber washer during operation of said lead feed mechanism.

5. A mechanical pencil comprising a hollow plastic barrel having separate upper and lower portions, a lead feed mechanism including a helically slotted feed tube and a longitudinally slotted guide tube, said guide tube being fixed in the lower portion of said barrel, and said feed tube being assembled in telescoped relation for rotation on said guide tube, and an operating sleeve associated with said feed tube and extending from the lower portion of said barrel for frictional contact with the upper portion of said barrel, said operating sleeve having an expanded portion positioned at the joint between the upper and lower portions of said barrel for aligning said barrel portions at this point.

6. A mechanical pencil comprising a hollow plastic barrel having separate upper and lower portions, a lead feed mechanism including a helically slotted feed tube and a longitudinally slotted guide tube spaced concentrically in said barrel, said guide tube being fixed in the lower portion of said barrel, and said feed tube being assembled in telescoped relation for rotation on said guide tube, an operating sleeve fitted snugly in the lower portion of said barrel, but free for rotation in said lower portion, and extending for frictional contact with the upper portion of said barrel, said operating sleeve being contracted at the end fitted in the lower portion of said barrel to grip said feed tube, and spacing members disposed in said operating sleeve for aligning said feed tube.

7. A mechanical pencil comprising a hollow plastic barrel having separate upper and lower portions, a lead feed mechanism including a helically slotted feed tube and a longitudinally slotted guide tube assembled in telescoped relation, a mounting sleeve fixed on said guide tube and in the lower portion of said barrel for securing said guide tube relative to said barrel portion, an operating sleeve fixed to said feed tube and extending from the lower portion of said barrel for frictional contact with the upper portion of said barrel, said operating sleeve having an expanded portion positioned at the joint between the upper and lower portions of said barrel for aligning said barrel portions at this point, and said mounting sleeve having an externally threaded portion extending from the writing end of said lower barrel portion, and a metal tip member internally threaded for assembly on the extending threaded portion of said mounting sleeve, the writing end of said barrel being shouldered, and said tip member being formed with a flange adapted to seat externally on said shoulder and thereby align the barrel with said tip member.
